United States Patent Office

Des. 207,956
Patented June 20, 1967

207,956

TARGET

Fred Michael Lamin, 116 Mansfield Road,
Nottingham, England

Filed Nov. 1, 1965, Ser. No. 87,962

Term of patent 3½ years

(Cl. D22—16)

FIG. 1

FIG. 2

FIG. 3

FIG. 4

FIG. 5

FIG. 1 is a perspective view of a target showing my new design;

FIG. 2 is a bottom plan view thereof;

FIG. 3 is an elevational view taken from one side thereof;

FIG. 4 is a top plan view thereof; and

FIG. 5 is a rear elevational view thereof.

I claim:

The ornamental design for a target, as shown.
